UNITED STATES PATENT OFFICE

2,426,934

KNIFE SHARPENER

George M. Jones, Jenkintown Manor, Pa., assignor to Ace Manufacturing Corporation, Philadelphia, Pa., a corporation of Pennsylvania

Application October 3, 1945, Serial No. 619,925

7 Claims. (Cl. 76—87)

1

The present invention relates to knife sharpeners and it relates more particularly to a new and improved knife sharpener of the so-called rotary disc type.

An object of the present invention is to provide a simple, inexpensive and efficient knife sharpener. Another object of the present invention is to provide a sharpener of the rotary disc type which can be manufactured from inexpensive materials and with simple operations to give an efficient, safe, attractive and low cost product for household use or the like.

Other objects and advantages of the present invention are apparent in the following detailed description, appended claims and accompanying drawings.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a side elevational view of one embodiment of the present invention, with discs and side wall omitted.

Figure 2 represents a vertical cross-sectional view of the embodiment in Figure 1.

Figure 3 represents a cross-sectional view generally along the line 3—3 of Figure 2.

Figure 4 represents a cross-sectional view generally along the line 4—4 of Figure 2.

Figure 5 represents a perspective view of the rotary disc and base assembly as it appears when removed from the housing.

Figure 6 represents a plan view of the base as it appears after having been stamped out or otherwise formed from sheet metal, but before having been bent into the final form shown in Figure 5.

Figure 7 represents a side elevational view of a modified form of the present invention.

Figure 8 represents a fragmentary cross-sectional view, on an enlarged scale, of the embodiment of Figure 7, illustrating how the knife sharpener can be affixed to a supporting surface or wall or the like.

Figure 9 represents a perspective view of a modified form of the rotary disc and base assem-

10 bly as it appears when removed from the housing.

Figure 10 represents a perspective view of the opposite side of that modification shown in Figure 9.

Figure 11 represents a side view of the modified form of sharpening disc shown in Figures 9 and 10.

Figure 12 represents a view in cross-section on 10 the line 12—12 of the modified form of sharpening disc shown in Figure 11.

Figure 13 represents a view in cross-section on 15 the plane of the axis of the modified discs shown in Figures 9—12 disclosing portions of the discs, 15 the washers, and the support therefor.

In one embodiment shown generally in Figures 1 to 6 of the drawings, I may provide a housing 10 which may be integrally formed of molded synthetic plastic or the like, appropriately 20 colored during the molding operation. The housing 10 is formed with a recess or chamber 11 which is open at the bottom and which is generally closed at the top, except for a slot or opening 12 whose function will be hereinafter described. Chamber 11 includes two small cavities 11—A in the base of housing 10.

A handle 13 is formed integrally with the housing 10 and a grooved thumb-rest 14 is provided on the top of the housing 10 intermediate the slot 30 12 and the handle 13.

A plurality of centrally apertured sharpening discs 15, of hardened tool steel or the like are rotatably mounted upon a pair of spaced shafts 16 and 17, alternately with smaller-dia-metered 35 spacer-washers 18.

The ends of the shafts 16 and 17 are mounted in semicircular notches 19 provided at the upper edges of the sides 20. A pair of generally outwardly extending flanges 21 are formed integrally with the base 22 of a support 23.

The support 23 can be stamped out of sheet metal, as shown in Figure 6, and can be provided with fold-lines 21—A intermediate the base 22 and the sides 20. The flanges 21 extend laterally beyond the lateral edges of the sides 20; the distance between the ends 21—B of the flanges 21 being approximately the same as, or slightly less than, the length of the chamber 11 as measured from the ends of the notches 11—A in the base of housing 10. Support 23 has notches 34 therein adjacent the sides of the flanges 21. These notches 34 insure that the flanges 21 do not abut the faces of the sides 20 when the sides 20 have been folded about the fold-lines 55 21—A.

As can be seen particularly in Figures 3, 4 and 5, the discs 15 on the two shafts 16 and 17 are staggered relative to each other (the discs 15 on the shaft 16 being opposite the washers 18 on the shaft 17 and vice versa) and overlap slightly.

The base 22 of the support 23 is provided, at its ends, with a pair of holes 24 whereby the support 23 can be affixed to the housing 10 by countersunk screws 25 as shown particularly in Figure 2. The flanges 21 are thus located in the cavities 11—A.

A pair of generally U-shaped shoulders 26 are integrally formed on the sides of the chamber 11 of the housing 10; each shoulder 26 extending on both sides of the slot 12.

Semi-circular notches 27 are formed at the bearing edges 28 of the shoulders 26; the notches 27 being in alignment with the notches 19 on the base flanges 21 so that, when the base 22 is fastened within the chamber 11 as shown in Figure 2, the four pairs of opposed notches 19 and 27 will generally enclose the ends of the shafts 16 and 17.

A central notch 29 is provided on the upper edge of each side 20 while a complementary projection 30 is formed on the lower edge 28 of each shoulder 26; the projections 30 fitting within the notches 29. The projections 30 and the notches 29 serve to center the sides 20 relative to the shoulders 26 and also serve as keying portions and act to prevent lateral shifting of the flanges 21 relative to the bearing edges 28 during operation of the knife sharpener.

The dimension C between the bottoms of the notches 19 and the fold-line 21—A plus the diameter of shafts 16 or 17 is approximately equal to or slightly greater than the dimension D (Figure 1) between the bottoms of the notches 27 and the base or bottom face of housing 10. Since the flanges 21 are somewhat flexible about the lines 21—C (where the flanges 21 join the base 22), the support 23 as a whole can be adjusted a few thousandths of an inch by tightening screws 25. This is possible because, as previously stated, the distance between the ends 21—B of the flanges 21 is slightly less than the length of the opening in housing 10 in which the flanges 21 are located. This adjustment compensates for any variation in the dimensions C or D.

In operation, the handle 13 is grasped with one hand, with the thumb resting against the grooved portion 14 and the sharpener is held firmly against a wall or table or the like to provide a rigid support.

The knife to be sharpened is grasped in the other hand and the edge of the knife is inserted within the slot 12 and is placed against the discs 15 at their line of intersection. The knife is then drawn firmly through the slot 12 so that the edge passes across the edges of the discs 15.

As can be seen from Figures 3 and 4, the discs 15 and the washers 18 are mounted upon the shafts 16 and 17 with slight clearances therebetween so that, as the knife edge moves across the discs 15, they are tilted somewhat and are rotated to provide proper sharpening action, as is well known in the art.

That is, the total transverse dimension of the sharpening discs and the washers is appreciably less than the length of the shafts intermediate the flanges. This, coupled with the fact that the central openings in the discs and the washers are slightly oversize relative to the shafts, pro-

vides a loose cantilever mounting for the sharpening discs whereby they are free to rotate in wobbling overlapping relationship so as to present the edges of the discs at acute cutting angles to the knife edge being sharpened upon movement of the knife edge along the plane of intersection of the sharpening discs. It is apparent that the housing 10 covers and conceals the greater part of the sharpening discs; only a relatively narrow upper overlapping zone being exposed.

The slot 12, in addition to exposing the sharpening zone of the discs, also acts as a guide and a guard for the knife edge being sharpened; the generally upright sides of the slot extending appreciably above the sharpening zone of the discs and preventing the knife blade from accidentally shifting laterally during the sharpening movements thereof.

It is apparent that the housing fully conceals the sharpening discs except at the sharpening zone. This protects the discs from dirt and water and also prevents accidental injury to the hands of the user.

In Figures 7 and 8, there is shown another embodiment of the present invention which generally resembles that of Figures 1 to 6 except that the housing 10—A is not provided with a handle or thumb-rest and, instead is intended to be more or less permanently fastened to a supporting surface or wall. As shown particularly in Figure 8, the housing 10—A may be provided, adjacent its lower edge, with corner eyelets 31 of metal or the like through which screws 32 can be passed to fasten the housing to a supporting wall 33.

The operation of the embodiment of Figures 7 and 8 is similar to that described hereinabove in connection with the embodiment of Figures 1 to 6; the knife edge being placed within the slot 12 and against the line of convergence of the discs 15 and moved laterally to give a sharpening action.

In Figures 9 through 12, there is shown a second embodiment of the present invention which also generally resembles that of Figures 1 to 6 except that the sharpening discs 15—A have a ring-shaped portion 15—B of relatively large diameter projecting from one surface thereof and a ring-shaped portion 15—C of relatively small diameter projecting from the opposite surface.

This construction permits all but two of the spacer-washers to be dispensed with. This is accomplished by assembling the sharpening discs 15—A with two portions 15—B abutting one another and two portions 15—C abutting one another alternately. This causes the sharpening discs to be spaced and not nested. Between one end of a pile of sharpening discs 15—A and a side 20, a washer 18—A abutting portion 15—B, is employed. At the opposite end of the other pile of discs 15—A, a washer 18—A, abutting the portion 15—C is located. These washers 18—A are the only two employed in this modification. The sharpening discs 15—A are spaced elsewhere by the projecting portions 15—B and 15—C which abut in pairs and thus keep the discs 15—A apart.

The novel knife sharpener of the present invention can be quickly, easily and inexpensively manufactured and assembled.

Thus, the housing 10 (or 10—A) can be formed

of any suitable synthetic resin or plastic in a single molding operation.

The support 23 can be stamped out of sheet metal in a single stamping operation and the flanges 21 can be readily bent up along the fold-lines 21—a shown in Figure 6.

The sharpening discs 15, the washers 18 and the metal shafts 16 and 17 are standard parts which are readily procurable.

The assembling of the knife sharpener requires only the mounting of the discs and washers upon the shafts, the positioning of the shafts upon the notches 19 of the base flanges 21, the insertion of the support 23 (together with the discs, etc.) within the chamber 11, and the fastening of the screws 25.

It is evident, therefore, that the novel knife sharpener of the present invention can be manufactured with a minimum cost in labor and materials.

Thus, the present invention provides a simple, low cost knife sharpener which, at the same time, is durable and efficient in operation.

The embodiment of Figures 1 to 6 permits the knife sharpener to be stored out of the way in drawer or the like and to be taken out when needed.

The novel placement of the handle 13 and the grooved thumb rest 14 permit the flat bottom of the sharpener to be held firmly against a supporting surface or wall to prevent accidental slipping or movement of the knife sharpener when in use.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described my invention, what I claim as new and desire to protect by Letters Patent, is:

1. A knife-sharpener comprising an integrally-formed housing having a bottom opening and a top slot, a pair of notched bearing surfaces integrally formed inside said housing adjacent the ends of said slot, a base of sheet-metal or the like fastened within said bottom opening, said base having a pair of spaced upwardly-extending flanges notched correspondingly to said bearing surfaces, a pair of spaced shafts disposed within said housing and supported at their ends intermediate opposed notches on said bearing surfaces and said flanges, and a plurality of sharpening discs rotatably cantably spacedly mounted on each of said shafts, the discs on the respective shafts being disposed in staggered overlapping relationship, said slot exposing only a relatively narrow overlapped zone of said discs.

2. A knife-sharpener comprising an integrally-formed housing having a bottom opening and a top slot, a pair of notched bearing surfaces integrally formed inside said housing adjacent the ends of said slot, a base of sheet-metal or the like fastened within said bottom opening, said base having a pair of spaced upwardly-extending flanges notched correspondingly to said bearing surfaces, said flanges being retained against shifting relative to said bearing surfaces by keying portions formed thereon, a pair of spaced shafts disposed within said housing and supported at their ends intermediate op-

10 posed notches on said bearing surfaces and said flanges, and a plurality of sharpening discs rotatably cantably spacedly mounted on each of said shafts, the discs on the respective shafts being disposed in staggered overlapping relationship, said slot exposing only a relatively narrow overlapped zone of said discs.

3. A knife-sharpener comprising an integrally-formed housing having an elongated handle and a grooved thumb-rest adjacent to said handle, said housing having a bottom opening and a top slot, a pair of notched bearing surfaces integrally formed inside said housing adjacent the ends of said slot, a base of sheet-metal or the like fastened within said bottom opening, said base having a pair of spaced upwardly-extending flanges notched correspondingly to said bearing surfaces, a pair of spaced shafts disposed within said housing and supported at their ends intermediate opposed notches on said bearing surfaces and said flanges, and a plurality of sharpening discs rotatably cantably spacedly mounted on each of said shafts, the discs on the respective shafts being disposed in staggered overlapping relationship, said slot exposing only a relatively narrow overlapped zone of said discs.

4. A knife-sharpener comprising an integrally-formed housing having a bottom opening and a top slot, a pair of notched bearing surfaces integrally formed inside said housing adjacent the ends of said slot, a base of sheet-metal or the like fastened within said bottom opening, said base having a pair of spaced upwardly-extending flanges notched correspondingly to said bearing surfaces, a pair of spaced shafts disposed within said housing and supported at their ends intermediate opposed notches on said bearing surfaces and said flanges, a plurality of sharpening discs rotatably cantably spacedly mounted on each of said shafts, the discs on the respective shafts being disposed in staggered overlapping relationship, said slot exposing only a relatively narrow overlapped zone of said discs, and means for fastening said housing to a supporting wall or the like.

5. A knife-sharpener comprising an integrally-formed housing having an elongated handle and a grooved thumb-rest adjacent to said handle, said housing having a bottom opening and a top slot, a pair of notched bearing surfaces integrally formed inside said housing adjacent the ends of said slot, a base of sheet-metal or the like fastened within said bottom opening, said base having a pair of spaced upwardly-extending flanges notched correspondingly to said bearing surfaces, said flanges being retained against shifting relative to said bearing surfaces by keying portions formed thereon, a pair of spaced shafts disposed within said housing and supported at their ends intermediate opposed notches on said bearing surfaces and said flanges, and a plurality of sharpening discs rotatably cantably spacedly mounted on each of said shafts, the discs on the respective shafts being disposed in staggered overlapping relationship, said slot exposing only a relatively narrow overlapped zone of said discs.

6. A knife sharpener comprising a housing having a bottom opening and a top slot formed therein, a base fastened within said housing, and two sets of sharpening discs disposed within said housing and carried by said base in spaced staggered overlapping rotatable cantable relationship, said slot exposing only a relatively narrow overlapped upper zone of said discs, each of said

discs having projecting from one face a portion of relatively large diameter and having projecting from its opposite face a portion of relatively small diameter, said portions of relatively large diameter abutting each other and said portions of relatively small diameter abutting each other to hold said discs spaced.

7. A knife sharpener comprising an integrally formed housing having a bottom opening and a top slot, a pair of notched bearing surfaces integrally formed inside said housing adjacent the ends of said slot, a base of sheet metal or the like fastened within said bottom opening, said base having a pair of spaced upwardly extending flanges notched corresponding to said bearing surfaces, a pair of spaced shafts disposed within said housing and supported at their ends intermediate opposed notches on said bearing surfaces and on said flanges, and a plurality of sharpening discs rotatably cantably spacedly mounted on each of said shafts, the discs on the respective shafts being disposed in staggered

10

5 overlapping relationship, said slots exposing only a relatively narrow overlapped zone of said discs, each of said discs having a ring of relatively large diameter extending from one of its sides and a ring of relatively small diameter extending from its opposite side, said rings of relatively large diameter abutting each other and said rings of relatively small diameter abutting each other to hold said discs spaced.
